UNITED STATES PATENT OFFICE

ARY C. CLARK AND ARTHUR L. GRAVES, OF IMPERIAL, CALIFORNIA; SAID GRAVES
ASSIGNOR TO IMPERIAL IRRIGATION DISTRICT, A CORPORATION OF CALIFORNIA

CANAL EXCAVATOR

Application filed August 6, 1928. Serial No. 297,816.

Our invention relates to excavators, or diggers, particularly adapted for making and maintaining canals or ditches of various widths and depths for irrigation purposes.

- 5 The objects of our invention are: First, to provide a machine of this class having a laterally extensible frame adapted to span ditches of various widths, said frame being extensible or contractable in width automatically by the propulsion of the machine forwardly or backwardly; second, to provide a machine of this class in which one of the supporting and propelling means at one side of the frame is adapted to be shifted angularly with respect to the general direction of motion of the machine so that such supporting and propelling means is automatically shifted outwardly or inwardly, depending upon the direction of angular shift; third, 20 to provide a machine of this class in which the supporting and propelling means or tractors at the opposite sides of the machine may be advanced in either direction in fixed parallel paths, or may advance in gradually diverging paths to the limit of the lateral extension of the machine, or in converging paths to the limit of the lateral contraction of the frame of the machine; fourth, to provide a machine of this class for securely holding the direction of the several tractors relative to each other, and also for securely locking the frame or the supporting tractors against lateral extension or contraction relative to each other; fifth, to provide novel means of shifting the 25 one tractor angularly with respect to the other or to the supporting frame; sixth, to provide a machine of this class in which the shiftable or flanking tractor is pivoted to the frame on a horizontal axis so as to reduce 30 to a minimum twisting strains upon the frame; seventh, to provide a machine of this class in which the several operating or propelling elements are operatively disconnected and are separately operable relative to, and 35 simultaneously with, and in opposite direction from each other, so that the machine may move in a straight line forwardly or backwardly, around slight curves, which may turn around substantially within its own area, and 40 whereby two tractors may move at substan- tially the same speed forwardly or backwardly even though the one tractor is shifted at an angle; eighth, to provide a machine of this class in which the separate operating units are separately driven by electric motors 45 operated by a common power plant; ninth, to provide a novel mechanism for angularly shifting one of the tractors relative to the other; tenth, to provide as a whole a novelly constructed machine of this class; and, 50 eleventh, to provide a machine of this class which is particularly simple and economical of construction proportionate to its functions, durable, efficient, easy to operate, and which will not readily deteriorate or get out of 55 order.
- With these and other objects in view, as will appear hereinafter, our invention consists of certain novel features of construction, combination and arrangement of parts 60 and portions, as will be hereinafter described in detail and particularly set forth in the appended claims, reference being had to the accompanying drawings and to the characters of reference thereon which form a part 65 of this application in which:
- Figure 1 is a plan view of our excavator in one form of construction, showing by dotted lines the tractor at one side of the machine shifted to various angular position; 70 Fig. 2 is a rear elevational view of our machine showing the same in position for digging a canal or ditch; Fig. 3 is a side elevational view thereof taken from the side of the flanking tractor, or the tractor adapted to be 75 shifted angularly with respect to the machine; Fig. 4 is a fragmentary sectional view on an enlarged scale taken through 4-4 of Fig. 2 showing the cross section of the slideable members comprising the laterally extensible 80 portion of the frame in one form of construction; Fig. 5 is a fragmentary sectional elevational view on an enlarged scale taken through 5-5 of Fig. 1 showing the mounting of the extensible portion of the frame on the 85 angularly shiftable tractor and showing the pivotal mounting thereon on horizontal and vertical axes, the view also being taken through 5-5 of Fig. 6; Fig. 6 is a fragmentary view in plan showing such pivotal 90
- 100

mounting and the means for controlling the shifting of the tractor relative to the frame of the machine; and, Fig. 7 is a fragmentary side elevation view thereof, showing its relation to the upper frame of the shiftable or flanking tractor.

Like characters of reference refer to similar parts and portions throughout the views of the drawings.

10 Our excavator in its preferred embodiment, as shown in the drawings, consists essentially of a main frame A, a pair of separate and separately controllable supporting and propelling means or tractors B and C, and an 15 excavator or excavating portion D carried by the main frame at the rear end thereof.

10 The supporting and propelling means, or the tractors, B and C, as shown, are of the track laying type of tractors, the one at the 20 right hand side being of considerably greater length than the so-called flanking tractor C at the left hand side of the machine. The main frame A is rigidly and preferably permanently supported at or near its right hand 25 side upon the larger or main tractor B, and is moved, shifted and tilted with the tractor B. The opposite or left hand side of the frame, which may be considerably shorter than the right hand side of the frame, is yieldably supported upon the flanking tractor C in a manifold manner, whereby the flanking tractor 30 may be extended or contracted laterally relative to the main tractor, tilted longitudinally upwardly or downwardly relative thereto, or 35 shifted horizontally, angularly thereto.

40 The lateral shifting of the tractors relative to each other is preferably effected by a laterally extensible frame which forms a part of the main frame. In Fig. 4 of the drawings is shown a form of such extensible portion, 45 designated E, and consists of a plurality of longitudinally shiftable and telescoping frame members, designated respectively 1, 2, 3 and 4 from the outer to the inner member. 50 These telescoping frame members are preferably rectangular in construction and built up of structural form, as shown. The outer member 1 forms part of the supporting or reinforcing of the main frame and is preferably positioned under the operating platform. The inner telescoping frame member 4, which is built up essentially of an H-beam having angles at the inner sides of its flanges, extends beyond all of the other telescoping supporting members and is provided at its extended end with an upwardly offset portion 4a at the extended end of which is provided a cylindrical or trunnion portion 4b.

55 The tractor C is provided with a fixed superstructure or frame 5 which extends a considerable distance above the upper tracks of the tractor C. At the upper end of this frame is mounted the power unit and gear transmission for driving the tractor C, as 60 will be described later. Intermediate the

upper end of this frame and the tracks of the tractor C are provided cross braces or supports 5a on which is mounted a large bearing plate 6. This bearing plate is provided at its central portion with a vertical opening 6a and at its upper end or side with a beveled bearing seat 6b of broad and inverted conical form. On the beveled bearing seat 6b is rotatably supported a conforming beveled bearing portion 7a at the under side of a journal member 7 through which the trunnion 4b, above described, extends and is rotatably mounted on an axis positioned horizontally and transversely to the bearing seat 6b and also transversely to the longitudinal extent 75 of the tractor C. The trunnion 4b is retained against longitudinal movement relative to the journal member 7 by a collar 8 at the end of the trunnion 4b extending to the opposite side of the journal member 7. The journal member 7 is retained in position relative to the bearing plate 6 by a vertical extension 7b of the journal member 7, and by a collar 9. This vertical extension 7b extends 80 downwardly from the journal member 7 through the vertical opening 6a in the bearing plate. The collar 9 is secured to the lower end of this vertical extension and engages a shoulder 6c in a recess at the under side of the bearing plate 6, as shown best in Fig. 5.

85 The bearing plate 6, and therefore the flanking tractor C secured thereto, is in this instance rotated relative to the journal member 7 and the frame of the machine by a worm gear 10 and a worm 11. The worm gear is only a fragmentary portion or segment of a worm gear and is secured to the forward side of the bearing plate 6. The worm 11 is secured to a spindle or shaft 12 which is revolvably mounted in a forwardly extended portion 7c of the journal member 7, and meshes with the segmental worm gear 10. The spindle 12 extends beyond the normally outer side of the frame 5 and is provided at its extended end with an operating hand wheel 13, which, in the structure here disclosed, is adapted to be operated by a secondary operator standing on the ground near the flanking tractor. As the hand wheel 13 is rotated 90 in either direction, preferably when the whole machine is advancing in either direction, the flanking tractor is rotated about its vertical axis, and may be shifted to either of the positions shown by dotted lines in Fig. 1 or to 95 any intermediate position.

100 Both the bearing plate 6 and the journal member 7 are provided with backwardly extended portions 6d and 7d which are superimposed. These rearwardly extended portions are provided with a plurality of conforming holes 6e and 7e through which is extended the pin 14 when any two holes in each of said members are aligned, for either 105 locking the tractor in its normal position 110

parallel to the tractor B or angularly relative thereto.

Thus, it will be seen that when the flanking tractor C, which is of relatively small construction and easily rotated, is rotated about its vertical axis, as described above and shown by dotted lines in Fig. 1, lateral force is automatically applied on the main frame A when the machine is propelled either forwardly or backwardly by tractors B and C. Since only the laterally extendable portion E is permitted to yield, the telescoping members of the extensible portion E are automatically shifted longitudinally relative to each other and transversely relative to the main frame to the limit of their longitudinal extension or contraction, or until the flanking tractor is again shifted to a position with its longitudinal axis parallel to that of the tractor B; that is, the telescoping members are extended or contracted with respect to each other when the machine is propelled while the tractor C is positioned angularly, no further extension or contraction being made when the machine is stopped, or when the limit of the extension or contraction of the telescoping members is reached, or when the tractor C is shifted with its longitudinal axis parallel to the longitudinal axis of the tractor B.

Although we have provided positive means on the members 6 and 7 for permitting angular shifting of the tractor C and thus preventing unintentional extension or contraction of the extendable portion of the frame, we have provided other means in connection with the extendable portion of the frame for securing the same against unwarranted extension or contraction, thus holding the two tractor units in fixed positions relative to each other. This securing means consists preferably of a plurality of bolts 21, as shown best in Figs. 2 and 4, each of which extends through two adjacent and engaging telescopic members of the extendable portion of the frame. Each of the bolts 21 is preferably fixed in the outer telescoping member of each pair and extends through a longitudinal slot in the inner telescoping member of each pair, as shown best in Fig. 2. When any of these bolts or clamp means are loosened, longitudinal extension or contraction of the corresponding telescoping members is permitted. When the desired extension or contraction of the extendable portion of the frame is effected, such bolts or clamp means are tightened to prevent unwarranted extension and contraction of the frame of the machine.

Since the tractor C and the excavating portion D of our excavator are shiftable in various ways and to considerable extents relative to the main frame A which is stationary on the tractor B, we have provided independent power units in the form of electric motors 31, 32, and 33 on and for driving, respectively,

the tractor B, the tractor C, and the excavating portion of the machine. These electric motors receive the electric current from generators 34 mounted on the main frame 1 and driven by an engine 35 which is preferably a gasoline engine. By so driving the various units, the excavating portion may be driven when desired and as rapidly as desired irrespective of the forward or backward motion of the machine; and the flanking tractor may be driven forwardly at the same speed as the tractor B, or at an angle thereto and at the same speed forwardly, or slower, or faster than the tractor B for moving around curves, or they may be driven in opposite directions so as to make as small a turn as possible. All such variations of direction and speeds are effected without complicated transmission mechanism, gear shifting apparatus, and the like.

The excavating portion of our machine is mounted on a frame 41 which is mounted on a pair of tracks 42 and 43 at the rear of the frame A and transversely with respect to the longitudinal axis of the machine. The excavating conveyer, which consists of a bucket conveyer, and designated 44 in the drawings, is mounted on the excavator frame 45 which is suspended by cables and sheaves from a backwardly extending arm of the frame 41, as shown best in Fig. 3. Although the excavator frame 45 is suspended in the manner described, it is prevented, to a certain extent, from swaying backwardly and forwardly relative to the supporting frame 41 by a rod 46 connected by a universal joint 47 to a slide 48 reciprocally mounted in a vertical direction on the frame 41. The one end of the excavator frame 45 is adapted to be raised or lowered in order to raise the operative portion of the bucket conveyer from the excavated canal or ditch, or for lowering the same thereinto. Such raising and lowering is effected by other cables 49, and sheaves 50 and 51, the sheave 51 being connected to the excavator frame and the other being suspended from a boom 52 mounted on the frame A. The motor 33 is mounted on the frame 45, which, as stated, is movable upwardly and downwardly, which is tilttable, and which is adapted to be moved transversely with respect to the frame A. Thus, the excavating conveyer may be operated in any position desired irrespective of its positions relative to the main supporting frame.

Though we have shown and described a particular construction, combination and arrangement of parts and portions, we do not wish to be limited to this particular construction, combination and arrangement, but desire to include in the scope of our invention, the construction, combination and arrangement substantially as set forth in the appended claims.

Having thus described our invention, what

we claim as new and desire to secure by Letters Patent is:

1. In a machine of the class described, a tractor, a frame rigidly supported on said tractor, a second tractor, a journal pivotally mounted on said second tractor on a vertical axis, means in connection with said frame for pivotally supporting said frame on a horizontal axis in said journal, means for 10 rotating the second tractor relative to the journal and for locking the same in various positions relative to each other, said means in connection with the frame being longitudinally extensible and contractable by the second tractor, and means for preventing the longitudinal extension and contraction of the means in connection with the frame.
2. In a machine of the class described, a freely laterally extensible frame, means for 20 supporting one side of the frame and for propelling the frame, and similar means at the opposite lateral side of the frame, the latter means being shiftable laterally with the laterally extensible portion of the frame 25 and shiftable about a vertical axis angularly with respect to the longitudinal axis of the frame and the first propelling means, said frame being capable of being extended and contracted when said frame is propelled while the latter means is positioned angularly 30 with respect to the frame.
3. In a machine of the class described, a freely laterally extensible frame, means for supporting one side of the frame and for 35 propelling the frame, similar means at the opposite lateral side of the frame, the latter means being shiftable laterally with the laterally extensible portion of the frame and shiftable about a vertical axis angularly with 40 respect to the longitudinal axis of the frame and the first propelling means, said frame being capable of being extended and contracted when said frame is propelled while the latter means is positioned angularly with respect 45 to the frame, and means for securing the second means against angular shifting and in angular shifted position relative to the frame.
4. In a machine of the class described, a 50 freely laterally extensible frame, means for supporting one side of the frame and for propelling the frame, similar means at the opposite lateral side of the frame, the latter means being shiftable laterally with the laterally extensible portion of the frame and shiftable about a vertical axis angularly with 55 respect to the longitudinal axis of the frame and the first propelling means, said frame being capable of being extended and contracted 60 when said frame is propelled while the latter is positioned angularly with respect to the frame, means for securing the second means against angular shifting and in angular shifted position relative to the frame, and other means for preventing the lateral extension and contraction of said frame, and other means for preventing the angular shifting of the second tractor and for holding the same in angular 65 position relative to the frame.

free extension and contraction of said frame.

5. In a machine of the class described, a freely laterally extensible frame, means for supporting one side of the frame and for propelling the frame, similar means at the opposite lateral side of the frame, the latter means being shiftable laterally with the laterally extensible portion of the frame and shiftable about a vertical axis angularly with 70 respect to the longitudinal axis of the frame and the first propelling means, said frame being capable of being extended and contracted when said frame is propelled while the latter means is positioned angularly with respect to the frame, and manual means for angularly shifting the second means relative to said frame and also returning said second means in a normal position relative to said frame.

6. In a machine of the class described, a main supporting frame having an extensible portion at one side, a tractor rigidly secured to the opposite side of the main frame for supporting said side of the frame and for propelling the frame, and a second tractor 80 for supporting the first mentioned side of said frame and also for propelling the frame, said second tractor being pivotally connected and shiftable angularly relative to the extensible portion of the frame and shiftable 85 laterally relative to the main portion of the frame, said extensible portion of the frame being adapted to be extended and contracted while the second tractor is shifted angularly relative to the frame and when the machine is propelled forwardly and backwardly.

7. In a machine of the class described, a main supporting frame having an extensible portion at one side, a tractor rigidly secured to the opposite side of the main frame for supporting said side of the frame and for propelling the frame, a second tractor 90 for supporting the first mentioned side of said frame and also for propelling the frame, said second tractor being pivotally connected and shiftable angularly relative to the extensible portion of the frame and shiftable laterally relative to the main portion of the frame, said extensible portion of the frame being adapted to be extended and contracted 95 while the second tractor is shifted angularly relative to the frame and when the machine is propelled forwardly or backwardly, means for preventing the lateral extension and contraction of said frame, and other means for preventing the angular shifting of the second tractor and for holding the same in angular 100 position relative to the frame.

In testimony whereof, we have hereunto set our hands at Imperial, California, this 11th day of July, 1928.

ARY C. CLARK.

ARTHUR L. GRAVES.
